UNITED STATES PATENT OFFICE.

WALTER ARTHUR FINLEY, OF FAIRMONT, WEST VIRGINIA.

EMBROIDERY-HOOP.

1,249,057.

Specification of Letters Patent.

Patented Dec. 4, 1917.

Application filed November 19, 1914. Serial No. 872,978.

To all whom it may concern:

Be it known that I, WALTER A. FINLEY, a citizen of the United States, residing at Fairmont, in the county of Marion and State 5 of West Virginia, have invented certain new and useful Improvements in Embroidery-Hoops, of which the following is a specification.

This invention relates to an improvement 10 in embroidery hoops, and one of the principal objects of the invention is to provide an improved means for compressing the outer ring of the hoop upon the inner ring, whereby to secure and maintain the cloth 15 upon the hoop.

Another object of the invention is to provide an improved lever operable means for compressing the outer split ring upon the inner one, including means for adjusting the 20 throw of the lever whereby the range of adjustment of the outer ring may be varied.

A further object of the invention is to provide a device of the class described which will be extremely simple, durable, efficient 25 in operation and inexpensive to manufacture.

With these and other objects in view which will become apparent as the description proceeds, the invention resides in the 30 construction, combination and arrangement of parts, hereinafter more fully described and claimed, and illustrated in the accompanying drawing, in which like characters of reference indicate like parts throughout 35 the several figures, of which—

Figure 1 represents a fragmentary view in elevation, portions being broken away, of an embroidery hoop constructed according to my invention, the lever being shown 40 in open position.

Fig. 2 represents a view similar to Fig. 1, the lever being shown in locked or closed position.

Fig. 3 represents a view similar to Fig. 1, 45 showing a modified form of the outer hoop and operating mechanism.

Fig. 4 represents a view of the same showing the lever in closed or locked position.

Fig. 5 represents a plan view of the mechanism shown in Fig. 3, and

Fig. 6 represents a detail elevational view, 50 partially in section of the adjusting sleeve and trunnion to which it is swiveled.

The form of hoop shown in Figs. 1 and 55 2 includes an inner continuous ring 5 and an outer split ring 6. One end 7 of the outer

ring overhangs the opposite end 8 thereof and is off-set from the body portion of the outer ring so as to be spaced a distance from the inner ring 5 substantially equal to or 60 slightly greater than the thickness of end 8 of the other ring. This off-set end 7 may thus overhang the end 8 in the manner indicated in Figs. 1 and 2.

A pair of ears 9 extend outwardly from 65 the outer or free end of off-set sections 7, and a pair of ears 10 extend outwardly from the free terminal of end 8 of the outer ring, the said ears 10 being positioned on both sides of off-set sections 7, so as to embrace 70 and guide the same between them. Pivoted at one end between ears 10, is a lever 11. The latter is substantially of an inverted U-shape in cross section. A threaded bolt or pin 12 is at one end pivotally connected to 75 lever 11 between its sides and adjacent the point 13 at which said lever is pivoted to ears 10. Bolt 12 at its pivot end is provided with an eye 14 through which a pin 15, carried by the walls of lever 11 extends. 80

The outer or opposite end of bolt 12 is threaded and has turned thereupon a hollow knurled sleeve or swivel nut 16. Sleeve 16 at its outer end is rotatably carried by a trunnion 17, which is pivoted by means of 85 its arms 18 between the ears 9 carried by off-set end 7 of the outer hoop ring. The structure of the sleeve and trunnion is indicated in Fig. 6. It will be noted that sleeve 16 carries a stud or pin 19 which extends 90 through trunnion 17 and has a head 20 counter-sunk in the trunnion. This structure allows of the sleeve being rotated relatively to the trunnion without danger of its being lost therefrom. 95

Lever 11 is indicated in open position in Fig. 1, and by forcing said lever downwardly into the position shown in Fig. 2 the outer ring will be tightened upon the inner ring of the hoop, so as to bind the cloth, 100 which has previously been disposed between the rings, securely upon the inner ring. It will be noted that the lever 11 is of a curvature substantially equal to the curvature of the rings, and that by reason of its being of 105 a channel or inverted U-shape, the bolt 12 and sleeve 16 are housed within the lever when the latter is in the closed position indicated in Fig. 2.

The embodiment indicated in Figs. 3, 4 110 and 5, provides a continuous inner ring 5^a and a split outer ring 6^a. The ends of the

latter do not overlap, but on the contrary are spaced slightly apart, so that in order to tighten this outer ring 6^a it will be necessary to draw the ends of the ring together 5 rather than to press them apart as occurred in the operation of the outer ring shown in Figs. 1 and 2. I employ a lever operated mechanism to obtain this result, substantially similar in principal of operation to 10 the mechanism I have described, the main difference being that the lever is operated in an opposite direction from that shown in Figs. 1 and 2.

In Figs. 3 to 5 inclusive the lever is indicated at 11^a and is pivoted at its inner end 15 at 13^a between a pair of elongated ears 10^a provided on one end of split ring 6^a. One end of a threaded bolt or pin 12^a is pivoted at 15^a between the walls of lever 11^a 20 in the manner similar to the manner in which the bolt 12 is pivoted to lever 11, and the opposite end of a bolt 12^a carries a sleeve 16^a similar to sleeve 16 and like the latter is swiveled to a trunnion 17^a pivoted 25 between a pair of ears 9^a carried by the opposite end of the split ring 6^a. The structure of the last mentioned sleeve and trunnion is exactly similar to that shown in Fig. 6. The bolt 12^a adjacent lever 11^a is bowed 30 upwardly as at 21, so as not to engage against the pin 13^a on which lever 11^a is pivoted, when said lever is in closed position as indicated in Fig. 4. The back of lever 11^a is slotted or recessed as at 22 to allow room for 35 the adjacent portion of bolt 12^a to play.

In the modified form just described, the outer ring is indicated in open position as in Fig. 3 and in closed or compressed position in Fig. 4, and it will be noted that in 40 closing or locking the ring lever 11^a is forced downwardly to the left or away from the opposite free end of the outer ring. This movement of the lever while being opposite to the movement of the lever indicated 45 in Figs. 1 and 2 obtains the same result, in that it draws the outer ring tightly upon the inner ring. The lugs 10^a are substantially equal to or slightly greater in dimensions than the lever 11^a so that when said lever is 50 in closed position it will be substantially housed between the lugs 10^a.

In both forms shown in the drawing, the throw of the lever, and consequently the range of adjustment of the outer ring, may 55 be varied by the operation of the same element, namely, the threaded sleeve or swivel nut 16^a. In the first embodiment shown the sleeve may be turned in such direction as to increase the distance between the pivot 60 points 13 and 18 in order to obtain an increased tightness of the outer ring when the lever is in locked position as indicated in Fig. 2, and in the embodiment indicated in Figs. 3, 4 and 5 the sleeve 16^a may be turned 65 to decrease the distance between the pivot

points 13^a and 18^a in order to secure an increased tightness of the outer ring when the lever is in locked position.

It will be noted that in both embodiments the point of connection of the lever and bolt is out of alignment with a straight line connecting the pivot points of the lever and sleeve or trunnion, and is between said straight line and the hoop, when the lever is in closed or locked position, so that the 70 tension of the outer hoop operates to maintain the lever in that position, rather than to tend to raise the lever from its locked position. In this manner the operation is 75 similar to that of a toggle lever, and the lever once having been locked is not likely to become accidentally unlocked but must be forced into open position in order to unbind or loosen the outer ring upon the inner one.

It will be noted in both embodiments, that 80 there are no projecting or sharp points or obstructions which might tend to catch the thread during the process of embroidering cloth upon the hoop. In both instances quick adjustment of the outer hoop may be 85 had by simply turning the sleeve or nut 16 or 16^a as the case may be in the direction desired in order that various thicknesses of 90 cloth may be accommodated.

Although I have described the preferred 95 embodiment of my invention, I may desire to make such changes in the construction, combination and arrangement of parts thereof as do not depart from the spirit of the invention and the scope of the appended 100 claims.

I claim:

1. An embroidery hoop including an inner ring, an outer split ring, ears provided in pairs on the adjacent ends of the split ring, a lever pivoted at one end between one pair of ears, a trunnion pivoted between the opposite pair of ears, an internally threaded sleeve or swivel nut swiveled at one end in said trunnion, a bolt threaded at 110 one end into the opposite end of said nut, the outer end of said bolt being pivotally connected to said lever, said nut adapted to be turned for varying the throw of the lever, whereby the range of adjustment of the split 115 ring may be varied.

2. An embroidery hoop including an inner ring, an outer split ring, a lever pivotally connected to one terminal of the split ring, a trunnion pivotally connected to the other terminal of the split ring, a bolt pivotally connected with the lever, and a nut threaded on the bolt and swiveled in the 120 trunnion.

3. An embroidery hoop including an inner ring, an outer split ring, a lever substantially U-shaped in transverse section pivotally connected with one terminal portion of the split ring and movable toward the ring in attaining closed position having its 125 130

open side directed toward the ring, and means connecting the lever with the other terminal portion of the split ring for tightening the split ring upon the inner ring 5 when the lever is moved into closed position, said means being housed within the lever when the latter is in closed position.

4. An embroidery hoop, including an inner ring, an outer split ring having one 10 free extremity offset and projecting over the

other extremity, a lever pivotally connected to one terminal of the split ring, a trunnion pivotally connected to the other terminal of the split ring, a bolt pivotally connected with the lever, and a nut threaded on the bolt and 15 swiveled in the trunnion.
